United States Patent Office

Des. 184,967
Patented Apr. 21, 1959

184,967

COLORANT DISPENSER

Jack B. Stuman, Rockford, Ill., assignor to Rockcote
Paint Co., Rockford, Ill., a corporation of Illinois

Application September 25, 1958, Serial No. 52,758

Term of patent 7 years

(Cl. D52—2)

Fig. 1

Fig. 1 is a perspective view of a colorant dispenser embodying my new design;

Fig. 2 is a top plan view thereof, as shown in Fig. 3;

Fig. 3 is a side elevational view thereof, the opposite side being a mirror image of this side; and

Fig. 4 is an enlarged fragmentary perspective view of a portion of the front of the colorant dispenser.

I claim:

The ornamental design for a colorant dispenser, substantially as shown and described.
